1,926,606

RECEPTACLE FOR DISK TALKING MACHINE RECORDS

Albert William Ward, Cricklewood, London, England, assignor to Victor Talking Machine Company, a corporation of New Jersey

Application January 28, 1931, Serial No. 511,787,
and in Great Britain February 5, 1930

9 Claims. (Cl. 312—10)

This invention relates to an improved receptacle for disk talking machine records, and the principal object of the invention is to provide means whereby record tablets when not in use, 5 can be conveniently disposed upon, over or adjacent the turntable of a talking machine.

Another object of the invention is to provide a receptacle for retaining a plurality of record tablets in stacked, non-playing position within 10 the casing of a phonograph of the portable type, for example, whereby the record tablets will be held secure against movement while the instrument is being carried about.

A further object of the invention is to provide 15 a record receptacle which, together with the record tablets, can be removed from a position on, over or adjacent the turntable with the greatest possible ease preparatory to using the machine.

Still another object of the invention is to provide 20 a record receptacle for a plurality of record tablets whereby the loading of an automatic phonograph, for example, is readily effected in a convenient manner.

A further object of the invention is to provide 25 a record receptacle which is adapted to serve as a hopper or magazine for a plurality of record tablets in connection with an automatic phonograph mechanism, for example, wherein record tablets are transferred from non-playing to playing position and vice-versa, or are removed from 30 the record tablet hopper or magazine and subsequently returned thereto after a period of sound reproduction, in an inverted position.

The device according to the invention comprises 35 a record tablet receptacle substantially in the form of a tray, which can be inserted in and removed from a talking machine cabinet or the like and is provided with means whereby it can be readily located upon the turntable.

40 Location of the receptacle on or over the turntable may be effected by co-operation of said device with the turntable spindle, with the edge of the turntable itself, with the sides of the cabinet or with any of these parts in combination. The receptacle when in position in the machine may rest with the whole of its weight upon the turntable or alternatively, means may be provided whereby the weight is taken by the motor board of the machine at a number of points distributed 45 around the turntable or opposite therefrom.

The receptacle may embody means for yieldingly engaging the record tablets to retain them in position in the receptacle or alternatively, means may be provided in the lid or cover of the machine, such means engaging parts of the

container to cause the latter to engage the tablets to retain them in position. Again means may be provided in the lid or cover to directly engage the uppermost record of the stack when the lid is closed. 60

The invention is illustrated in the accompanying drawing in which

Fig. 1 is an end elevation partly in section of a talking machine of the kind known as portable, in the closed position and to which the device according to the invention has been applied. 65

Fig. 2 is a perspective view of the detachable record receptacle.

The record receptacle is formed of two strips 1, 2 of sheet metal connected together as by spot welding to form an X. At the point of intersection of the two strips 1, 2 an aperture 3 is formed, this aperture being of a size to pass freely over the end of the turntable spindle 4 projecting upwards from the turntable 5 of a talking machine (Fig. 1). The strips of sheet metal 1 and 2 at suitable points 6 in their length, corresponding to the diameter of the records 7 to be held, are bent downwards and outwards as shown at 8 (Fig. 2) then upwards as at 9, 80 then inwards as at 17 and finally downwards as at 10 to form closed loops at the four ends of the two metal strips 1, 2 these loops extending partly above and partly below the straight portions of the strips. The loops may be closed by soldering, welding or otherwise securing the ends 10 of the loops to the flat parts of the strips, though in the case illustrated they are shown as being open. The parts 10 of the loops above the flat portions of the metal strips carry pads 11 of thick felt or other suitable yielding material for engaging the edges of the records placed in the receptacle, the pieces of felt 11 being secured by an adhesive to the surfaces of the parts 10. 85

The upper ends of the pairs of metal loops at 95 opposite sides of the receptacle may be connected by metal rods 14 which brace the structure and serve also as handles whereby the receptacle together with the records contained therein can be lifted bodily from the position in the machine 100 when the latter is to be used. These metal rods 14 forming the handles may be conveniently mounted by passing their ends through the fold 17 at the upper end of the loops.

The handles 14 may with advantage be shaped 105 to lie close to the side walls 15 of the lid of the machine cabinet (Fig. 1) when the latter is closed, and in this position they may co-operate with wedge-like members 16 carried in the lid of the machine to exert an inward pressure upon the 110

upper portions of the loops, thereby pushing the felt pads 11 into firm contact with the edges of the records in the receptacle, the records being thereby held against movements when the lid of 5 of the machine is closed.

Where this arrangement is employed the loops are with advantage left unclosed as shown, as the movement of the parts of the loops carrying the pads 11, under the pressure of members 16 is 10 thereby facilitated.

If desired, studs such as are indicated at 18 in Fig. 1 may be provided on the motor board 13, these studs engaging the lower parts 8 of the loops to limit the extent to which the receptacle 15 can move about the turntable axis.

It will readily be seen that with a record receptacle such as has been described above, the records are held firmly in a safe and very convenient position within the machine when the 20 latter is not in use, and this is of particular advantage in the case of portable machines. Furthermore, the records, when required for use can, with the greatest of ease be removed at once and collectively by lifting and removing the receptacle 25 from the machine. The receptacle may still serve as a housing for the records when removed from the machine and placed upon a table or other appropriate support.

The device possesses the further advantage that 30 it obviates the sliding of one record over another as is necessary with record storage arrangements at present known for use within machines, such as the pockets usually provided in the lids of portable machines. In consequence wear and 35 tear on the records is lessened.

Although I have shown and described certain specific embodiments of my invention, I am fully aware that many modifications thereof are possible. My invention, therefore, is not to be restricted except insofar as is necessitated by the 40 prior art and by the spirit of the appended claims.

I claim as my invention:

1. A device for storing disk talking machine 45 records comprising a receptacle adapted to receive the records therewithin, said receptacle having an aperture therein whereby said receptacle is adapted to be threaded on a phonograph over a turntable spindle, and means adapted to 50 co-operate with the periphery of the turntable to locate the receptacle with respect to the turntable when said receptacle is positioned thereon, said means serving as legs for the receptacle when removed from the turntable.

55 2. A disk talking machine record receptacle comprising a pair of metal strips connected together to form an X, said strips having an aperture at their point of intersection and loops formed at the ends of said strips to form abutments for confining the records within said receptacle, said loops serving also as supporting means for said receptacle.

60 3. A receptacle for sound record tablets comprising a pair of angularly related members with the free end portions thereof bent upon themselves to form depending supporting members and upstanding abutment members, and means

connecting alternate pairs of end portions of said angularly related members.

4. A receptacle for sound record tablets comprising a pair of intersecting members with the free end portions thereof bent upon themselves to form depending supporting members and upstanding abutment members, and means connecting alternate pairs of end portions of said intersecting members. 80

5. A receptacle for sound record tablets comprising a pair of angularly disposed members having an aperture therein at their point of intersection, the free end portions of said members being bent upon themselves to form depending supporting members and upstanding abutment members, and means connecting alternate pairs of end portions of said angularly related members. 85

6. In combination, a phonograph including a cabinet and a turntable, a receptacle for record tablets adapted to be disposed on said turntable and comprising a pair of angularly disposed members having an aperture therein at their point of intersection, loops formed at the ends of said angularly disposed members to form supporting means for said receptacle and abutment members for confining the record tablets within said receptacle, resilient pads carried by said abutment members, and means carried by said phonograph for urging said abutment members 100 and pads into contact with the edges of said record tablets. 90

7. A receptacle for sound record tablets comprising a pair of intersecting members having an aperture therein at their point of intersection and adapted for registration with a turntable spindle, the end portions of said members being bent upon themselves to form supporting members and abutment members, pads of resilient material secured to the inner faces of said abutment members, and bracing rods connecting alternate pairs of end portions of said intersecting members, said supporting members being adapted to locate said receptacle over a turntable. 105

8. A receptacle for sound record tablets comprising a pair of angularly disposed members having an aperture therein at their point of intersection, the free end portions of said members being bent upon themselves to form depending supporting members and upstanding abutment members, bracing rods connecting alternate pairs of end portions of said angularly related members, and pads of resilient material secured to the inner faces of said abutment members. 110

9. A receptacle for receiving record tablets comprising a pair of metal strips connected together to form an X and having an aperture at their point of intersection, loops formed at the outer ends of said strips to form abutments for confining the record tablets within said receptacle, said loops serving also as supporting means for said receptacle, pads of yielding material on the inner faces of said loops for engaging the edges of the tablets in the receptacle, and bracing rods connecting opposite pairs of loops. 115

ALBERT WILLIAM WARD.
